Specification for Design.

Patented Feb. 22, 1921.

Application filed September 3, 1919. Serial No. 321,472. Term of patent 14 years.

To all whom it may concern:

Be it known that I, **HENRY MILLER LAMBERT**, a citizen of the United States, residing at Portland, in the county of Multnomah and State of Oregon, have invented a new, original, and ornamental Design for Automobile-Tires, of which the following is a specification, reference being had to the accompanying drawing, forming a part thereof.

Figure 1 is a perspective view showing the tire.

Fig. 2 is a side elevation of the same.

I claim:

The ornamental design for an automobile tire substantially as shown.

HENRY MILLER LAMBERT.
